US00D726169S

(12) **United States Design Patent**
Powell et al.

(10) **Patent No.:** **US D726,169 S**
(45) **Date of Patent:** **** Apr. 7, 2015**

(54) **CASE**

(71) Applicant: **Incipio Technologies, Inc.**, Irvine, CA (US)

(72) Inventors: **Mark Andrew Powell**, Costa Mesa, CA (US); **Blake Hunter Robertson**, La Mesa, CA (US); **Timothy Alan Hemesath**, Huntington Beach, CA (US)

(73) Assignee: **Incipio Technologies, Inc.**, Irvine, CA (US)

(**) Term: **14 Years**

(21) Appl. No.: **29/433,294**

(22) Filed: **Sep. 27, 2012**

(51) LOC (10) Cl. **14-03**

(52) U.S. Cl.

USPC **D14/250**

(58) **Field of Classification Search**

USPC ..... D14/138 G, 138 AD, 138 AB, 138 AA, D14/203.8, 203.5, 250, 251, 252, 253, 217, D14/496, 440, 346, 248, 238.1, 137, 356, D14/391, 392, 455, 456; D3/218, 215, 201, D3/247, 269, 273, 301, 303; 220/4.02; 361/679.56; 455/575.1, 575.8; 206/305, 320, 251, 45.2

See application file for complete search history.

(57) **CLAIM**

The ornamental design for a case, as shown and described.

DESCRIPTION

FIG. 1 is a front perspective view of a case.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top end view thereof; and,

FIG. 8 is a bottom end view thereof.

The dash-dash broken lines in the drawings illustrate portions of the case which form no part of the claimed design. The dash-dot-dash broken lines define the bounds of the claim and form no part thereof.

1 Claim, 6 Drawing Sheets
